CLAIM

The ornamental design for a nasal dilator, as shown and described.

DESCRIPTION

FIG. 1 is a top plan view of a first embodiment of a nasal dilator showing our new design, the bottom plan view being flat and unornamented, and not seen in use;

FIG. 2 is a side view showing the dilator being in use, the broken line showing of human facial features being directed to environment and for illustrative purposes only; the broken lines form no part of the claimed design;

FIG. 3 is a representative drawing showing a three-quarter perspective view thereof.

FIG. 4 is a top plan view of a second embodiment of the nasal dilator, the bottom plan view not seen in use;

FIG. 5 is a side view showing the dilator being in use, the broken line showing of human facial features being directed to environment and for illustrative purposes only; the broken lines form no part of the claimed design; and,

FIG. 6 is a representative drawing showing a three-quarter perspective view thereof.
